(57) **CLAIM**

We claim the ornamental design for a dehumidifier, as shown and described.

DESCRIPTION

FIG. 1 is a front view of a dehumidifier according to the invention;

FIG. 2 is a left view;

FIG. 3 is a top view;

FIG. 4 is a bottom view;

FIG. 5 is a right side view;

FIG. 6 is a rear view;

FIG. 7 is a sectional view taken along line A—A in FIG. 1;

FIG. 8 is a sectional view taken along line B—B in FIG. 1;

FIG. 9 is a perspective upper left rear view; and,

FIG. 10 is a perspective lower left rear view.

The sectional view of FIGS. 7 and 8 are provided only for the purpose of additional disclosure of the external shape of the invention.
